[57] ABSTRACT

An improved circuit-interrupter is provided having an improved operating mechanism for operating the separable contacts of the circuit-interrupter unit including a novel reverse-current loop structure enabling the

separable contacts to be magnetically closed under higher contact pressure during the existence of high-fault conditions, and, on the other hand, when it is desired to open the separable contacts of the improved circuit-interrupter under heavy-fault conditions with the contacts welded closed, the improved operating mechanism, including the reverse-current loop structure, operates in the opposite manner to assist the operating mechanism to open and to separate the separable contacts of the circuit-interrupter.

The improved invention additionally contemplates an improved magnetic means associated with the operating mechanism for applying additional contact closing force to hold the contacts closed under additional increased force created magnetically and instantaneously at the most appropriate time with the application of the high-fault conditions. Additionally, the same magnetic means is operable, taken in conjunction with the improved operating mechanism of the instant invention, to assist the opening of welded-closed contacts during the opening operation of the circuit-interrupter by a novel relocation of the fulcrum point, which is applicable and which functions in dependence upon either the energization or the non-energization of the operating magnet structure of the operating mechanism for the improved circuit-interrupter of this invention.

CIRCUIT-INTERRUPTER

CROSS-REFERENCES TO RELATED
APPLICATIONS

A related patent application by A. W. Hodgson, Ser. No. 481,423, filed June 20, 1974 entitled "Improved Movable Contact-Stem Operator For A Vacuum-Type Circuit-Interrupter," and assigned to the assignee of the instant patent application, discloses and claims the means for adjustment of the movable contact-stem operator for the movable contact of the circuit-interrupter disclosed herein.

BACKGROUND OF THE INVENTION

Circuit-interrupters particularly of the vacuum-type are relatively new on the commercial market, and have enjoyed only limited success due to several severe shortcomings. In an effort to minimize the most serious of these shortcomings, the vacuum-interrupter have found it necessary to use contact materials which are susceptible to welding. The welding problem, however, can be minimized by the use of contact and weld-breaking forces approximately ten times those usually found in a conventional air-break contactor of comparable rating.

Vacuum-interrupters having the most desirable interrupting characteristics and longest contact life have been found to weld at currents considerably below their interrupting limit, so that the interrupting rating of a contactor using these vacuum-type circuit-interrupters is limited by the ability of the actuating or operating mechanism to overcome the welding problem, rather than by the arc-interrupting ability of the vacuum-type circuit-interrupter.

A three-pole contactor having a magnet and frame assembly proportioned to meet the design requirements of the vacuum-interrupter, and still have a reasonable mechanical life would be much too large and costly to compete with existing air break contactors which require only a fraction of the contact force. As result of this "squeeze," presently available vacuum-type contactors, are a design compromise which do not completely satisfy the requirements of the vacuum interrupter, and as a result do not perform as well as existing available air-break contactors.

The very high contact forces mentioned above are required only when it is necessary to obtain the maximum momentary current rating of the vacuum-interrupter, which is in the event of a power-system fault. Since the contactor may seldom see this current condition in actual service, a contactor designed to continuously provide these high contact-closing forces would represent a rather inefficient use of space and material.

A reasonable-sized operating magnet, coupled to the interrupter shaft through a toggle mechanism, or other system of levers, could be devised to develop high contact closing forces, but the high mechanical advantage of this mechanism would act to reduce the contact-operating speed far below the values recommended for the vacuum interrupter. The high mechanical advantage of this mechanism would, in addition, result in low or diminished contact overtravel, which, in turn, would make frequent adjustment of contact overtravel necessary.

Reverse-current loops have been employed in the past to increase the contact-closing forces under heavy fault conditions, but have had the tendency to override

the operating magnet. A reverse-current loop of this type, designed to supply the required contact-closing forces of a three-pole vacuum contactor, would exert so much force that the reverse-current loop would hold the contacts and magnet closed even after the magnet is de-energized. A weak reverse-current loop of this type would not hold the contacts closed, but would act to reduce opening speed and weld-breaking forces, which is also undesirable.

SUMMARY OF THE INVENTION

In the improved vacuum-type circuit-interrupter and mechanism of the present invention, the contact closing springs, operating magnet and other structure are proportioned to provide the proper contact closing forces sufficient to insure satisfactory performance under motor starting, running, and locked-rotor conditions for the maximum sized motor with which the contactor will be used. The operating mechanism for the separable contacts of the vacuum-type circuit-interrupter is such that a reverse-current loop is employed in conjunction therewith which has two oppositely-directed functions. In the closed-circuit position of the circuit-interrupter, or contactor, with the magnet energized, the fulcrum point of the reverse-current actuating arm is so located that upon a sudden increase of the current magnitude passing through the circuit-interrupter, or stated otherwise, under heavy-fault conditions existing in the controlled circuit, the magnetic forces in the reverse-current loop structure are directed to increase the contact-closing forces, thereby assisting the contact-spring pressure provided by the operating mechanism itself.

However, when it is desired, on the other hand, to open the contacts of the vacuum-type circuit-interrupter, or contactor, the de-energization of the operating magnet will be reflected through the disclosed linkage structure to change the location of the fulcrum point of the reverse-current actuating arm to thereby bring about an opposite function or effect of the reverse-current loop structure, or in other words, to redirect the forces created by the reverse-current loop structure, so that at this time the magnetic forces, generated by the reverse-current loop structure, actually assist the operating mechanism to open the separable contacts, and to break any welded condition existing at the contacts themselves.

Thus, the improved reverse-current loop structure of the present invention has two important functions. The first function is to increase the contact-closing forces, thereby assisting the contact-pressure springs in the closed-circuit position of the circuit-interrupter, when the magnet structure is energized, under the conditions of high-fault current passing through the interrupter. In this case, conceivably a remote circuit-breaker would be desired to open the circuit rather than the contactor, and the magnet would remain energized as desired. Depending on whether the operating magnet of the contactor is energized or not, depends upon whether or not the fulcrum point of the reverse-current actuating arm changes, and thereby affects the function and operation of the reverse-current loop system.

Assuming, for instance, that it is desired to open the circuit-interrupter, or contactor, the de-energization of the operating magnet structure will effect automatically a relocation of the fulcrum point of the reverse-current actuating arm and thereby drastically change the operating function of the reverse-current loop sys-

tem to thereby result in an entirely oppositely-directed force, this time a force directed to open the separable contacts and thus to break any welding conditions existing therat.

In the improved operating mechanism of the instant invention there is associated with the rotatable contact-operating arm an abutment member, such as a plate, for example, which is associated with the contact-pressure spring, and a reverse-current loop arm pivotally mounted to the contact-actuating arm has a nose portion bearing on said abutment member or plate, and operable during the de-energized condition of the magnet to act in an opening direction against said abutment plate. The fulcrum point is at the pin 107, as shown in FIG. 20, which is between the pivot shaft 132 and the reverse-current loop 221, 222. Thus, magnetic forces are brought into play to redirect the reverse-current loop effect, and to pry, in effect, the welded contacts apart, and thereby assist the opening accelerating springs of the circuit-interrupter or contactor.

In more detail, the reverse-current loop system of the present invention comprises a metallic conducting arm carrying the line current to the interrupter contacts, and pivotally mounted on the same pivot shaft location at which the rotatable contact operating arm pivotally connects to the movable contact stem of the vacuum-interrupter. By thus being pivoted to the movable contact stem with the rotatable contact-actuating arm during heavy-fault current condition, the magnet repelling effect between the sides of the loop forces the separable contacts more firmly closed under high-fault conditions, when the magnet is energized, as is desired.

On the other hand, during the opening operation, when the operating magnet is de-energized, and the operating mechanism is stalled at the contact-touch point, due to a welded condition existing at the separable contacts; or in other words, the contacts are, in fact, welded closed, the reverse-current loop arm acts in a manner to break the contact weld by relocating the fulcrum point, of the reverse-current actuating arm so that it now exists at the pivot point for the rotatable contact arm. The fulcrum point is at pin 107, as shown in FIG. 20.

Another very important feature of the present invention is the structure for supplying or feeding series current to the reverse-current loop arm, so that it does not oppose or tend to neutralize the magnetic action of the reverse-current loop arm. This is achieved by a special stationary current-feed circuit, which locates the current-feeding arms in roughly the same plane as the movable portion of the reverse-current loop arm, so that, the fact, the magnetic effect, generated at the two stationary current-feed arms, is to increase and augment the magnetic effect exerted on the movable portion of the reverse-current loop-arm structure.

BRIEF DESCRIPTION OF THE DRAWINGS

FIG. 1 is a perspective view of motor-starter equipment including two motor starters disposed in superimposed relation together with their disconnecting-switch structures;

FIG. 2 is an enlarged view looking into the interior of a cell-structure adaptable for accommodating the improved roll-in vacuum-type circuit-interrupter structure of the instant invention, with the access doors for the low and high-voltage compartments being open;

FIG. 3 is a side-elevational view of the right side of the truck-mounted contactor, or interrupter assembly of the instant invention;

FIG. 4 is a side-elevational view of the lefthand side of the truck-mounted vacuum-interrupter assembly of the present invention;

FIG. 5 is a front elevational view looking at the front of the truck-mounted vacuum-type circuit-interrupter assembly of the present invention;

FIG. 6 is a vertical sectional view taken substantially along the line VI—VI of FIG. 5 with the separable-contact structure closed;

FIG. 7 is an enlarged detailed view of the operating linkage and mechanism structure of FIG. 6, again the separable contacts of the vacuum-type circuit-interrupter assembly being illustrated in the closed-circuit position with the operating magnet energized;

FIG. 8 is a fragmentary vertical section view taken substantially along line VIII—VIII of FIG. 7, again the contact structure being shown in the closed-circuit position;

FIG. 9 is a view similar to that of FIG. 7, but illustrating the separable contacts of the vacuum-interrupter unit in the fully-open circuit position with the operating magnet de-energized;

FIG. 10 is an exploded perspective view of the several parts employed in conjunction with the improved operating mechanism of the instant invention;

FIG. 11 is a somewhat diagrammatic view of the component parts of a motor-starter equipment for controlling motor installations with the disconnecting switch shown closed, and also the contactor assembly being shown in the closed-circuit position, the truck-mounted elements being illustrated in their in-cell operating condition;

FIG. 12 is a top plan view of the reverse-current feeder circuit illustrating the structure thereof;

FIG. 13 is a side-elevational view of the reverse-current feeder structure of FIG. 12;

FIG. 14 is a front elevational view of a component part of the improved reverse-current feeder circuit of FIGS. 12 and 13;

FIG. 15 is a diagrammatic view illustrating a single-acting reverse-current loop structure with the contacts (not shown) closed, and electrical current passing through the reverse-current loop structure;

FIG. 16 illustrates diagrammatically a double-acting reverse-current loop structure utilizing some of the principles of the present invention, but illustrating a condition of a feeder connection structure, which is not commercially appropriate or desirable, the contact structure (not shown) being illustrated in the closed-circuit position, and again electrical current being illustrated as passing through the double-acting reverse-current loop;

FIG. 17 illustrates diagrammatically the improved relocation of the feeder circuit structure of FIG. 16, in which the double-acting reverse-current loop is adversely magnetically affected by the particular feeder circuit arrangement illustrated in FIG. 17, which is, of course, undesirable;

FIG. 18 illustrates diagrammatically the closed-circuit position of the vacuum-type circuit-interrupter of the present invention, illustrating the passage of current through the reverse-current loop, illustrating the location of the pivot point or fulcrum point for the reverse-current loop arm, with the operating magnet energized, and during the existence of high-fault current

conditions existing in the separable contacts of the vacuum-type circuit-interrupter, the latter being illustrated as in the closed-circuit position;

FIG. 19 is a sectional view taken substantially along the line XIX—XIX of FIG. 18;

FIG. 20 illustrates a de-energized condition of the vacuum-type circuit-interrupter of FIGS. 18 and 19, showing a relocation of the pivot point or fulcrum point for the reverse-current loop arm structure, and the magnetic repulsive forces encountered, the view also illustrating the improved feeder-current connections to the reverse-current loop-arm;

FIG. 21 illustrates a fragmentary sectional view taken along the line XXI—XXI of FIG. 20, illustrating the current-flow conditions, and only showing the feeder-current connector system;

FIG. 22 is a sectional view taken substantially along the line XXII—XXII of FIG. 20 illustrating diagrammatically the magnetic lines of force associated with the improved feeder-current system of the present invention;

FIG. 23 illustrates a sectional view taken through the improved shoulder-bolt and movable-contact operator connection for actuating the movable-contact stem of the vacuum-type circuit-interrupter of the present invention;

FIG. 24 is an enlarged side-elevational view of the improved movable-contact operator utilized;

FIG. 25 is a front-elevational view of the improved movable-contact operator of FIG. 24;

FIG. 26 is a top-plan view of the improved movable-contact operator of FIG. 24;

FIG. 27 is an inverse plan view of the improved movable-contact operator of FIG. 24;

FIG. 28 illustrates in side elevation the accurately-machined lower interrupter support-plate utilized in the present invention;

FIG. 29 is an inverted plan view of the accurately-machined interrupter support structure of FIG. 28;

FIG. 30 is a front-elevational view of the improved accurately-machined interrupter support of FIGS. 28 and 29;

FIGS. 31—33 are enlarged detail views of the top interrupter clamp for connecting to the stationary contact stem of the vacuum interrupter;

FIG. 34 illustrates diagrammatically the wiring diagram for the starter assembly of the present invention; and

FIGS. 35—37 illustrate an application of the mechanism to a modified-type of arc-interrupting structure.

DESCRIPTION OF THE PREFERRED EMBODIMENT

The present invention has particular applicability to high-voltage motor starters 1 designed for starting and controlling alternating-current motors. Generally, these starters 1 are supplied in a steel floor-mounted enclosure 2, such as set forth in FIG. 1. The steel floor-mounted enclosure 2 may, for example, accommodate two motor starters starters 1, as actually shown in FIG. 1 disposed in superimposed relation.

As set forth in FIG. 11, each high-voltage motor-starter apparatus 1 comprises a cabinet housing 2 in which high-voltage modular plug-in assemblies corresponding to an isolating-switch assembly 3, a power-fuse assembly 5 and a contactor assembly 7 are secured. The cabinet housing 2 is illustrated in FIG. 2 as comprising panels 9—11 and supporting structure 13 as-

sembled to form a front-entry single-compartment cabinet with access provided by hinged access doors 15 and 17. Mounted on the interior surface of the back panel 10 are electrical terminal assemblies 19 and 21 which electrically engage an isolating-switch assembly 3 and the contactor assembly 7, respectively. The three-phase output power developed by the high-voltage apparatus 23 is conducted through cables 25, which pass through current transformers 27 to a load terminal assembly 29 for connection to a remote electrical circuit (not shown). This circuit could, of course, be motor equipment. Secured to the interior surface of the right-hand panel of the cabinet housing 2 is the low-voltage circuitry 31, which is electrically connected through suitable transformer means 33, to provide safe operating voltages for the low-voltage control devices.

The high-voltage motor-starter apparatus 23 of FIG. 11, for example, may require a single contactor assembly 7, and therefore supports the compact modular packaging scheme illustrated, in which the modular assemblies 3, 5 and 7 can be quickly removed from the housing cabinet 2 merely by sliding the assemblies 3, 5 and 7 forward through the cabinet opening provided by the access door 15.

The high-voltage motor-starter apparatus, schematically illustrated in FIG. 11, is set forth, in detail, in the following patents: U.S. Pat. No. 3,602,680, issued Aug. 31, 1971 to Alfred W. Hodgson; U.S. Pat. No. 3,639,873, issued Feb. 1, 1972 to Alfred W. Hodgson; U.S. Pat. No. 3,621,339, issued Nov. 16, 1971, to Alfred W. Hodgson; U.S. Pat. No. 3,264,431, issued Aug. 2, 1966 to A. W. Hodgson; U.S. Pat. No. 3,264,432, issued Aug. 2, 1966 to A. W. Hodgson et al.; U.S. Pat. No. 3,264,433 issued Aug. 2, 1966 to R. D. Clark, Jr. et al.; and U.S. Pat. No. 3,290,468 issued Dec. 6, 1966 to R. D. Clark, Jr. et al.

Sidewalls of the modular assemblies 3, 5 and 7 cooperate in an overlapping relationship in the cabinet housing 2 to define two cabinet compartments "A" and "B." Compartment "A" is designated the high-voltage component compartment with access provided by door 15, and compartment "B" is designated the low-voltage circuitry compartment with access provided by door 17.

As seen more clearly in FIG. 11, the isolation-switch assembly 3 comprises a rotatable handle mechanism 35, which controls the positioning of electrical contacts 37 to engage and to disengage electrical contact with the main power lines which terminate at the electrical terminal assembly 19. The location of the isolation switch assembly 3 in the cabinet housing 2 is selected to position the handle mechanism 35 at a convenient operator height.

The handle mechanism 35 is described in more detail in U.S. Pat. No. 3,264,431 issued Aug. 2, 1966, and assigned to the assignee of the present invention.

Access to the high-voltage compartment "A" is prevented by an interlock system (not shown) when the handle mechanism 35 is in either the "OFF" or "ON" position. Access to compartment "A" is permitted when the handle mechanism 35 is rotated to a horizontal position (not shown). A spring-loaded pin (not shown) must be manually depressed before the handle mechanism 35 can be rotated, thus preventing inadvertent operation of the handle mechanism. Access to the low-voltage compartment "B" is provided by the door 17 regardless of the position of the handle mechanism 35.

The contactor assembly 7 comprises electrically isolated contactor poles 39, 41 and 43 which represents commercially-available components, such as the Westinghouse Electric Corporation contactor Type LF-50V430 contactor. Contactor electrical terminal 45, as illustrated in FIG. 6, engages electrical terminal assembly 21 to supply voltage through the cables 25 to the remote load, which may be a motor installation.

The isolation switch assembly 3 is slidably positioned within the cabinet housing 2 by outwardly protruding flanges which engage horizontal guide tracks 47 (FIG. 2).

Due to the weight of the contactor assembly 7 it is generally located in the bottom section of the cabinet housing 2. The positioning of the contactor assembly 7 within the cabinet housing 2 is accomplished by inserting the wheels 49, which are affixed at the four corners of the base 51 of the assembly 7, into the guide tracks 53 (FIG. 2) and rolling the assembly 7 into the cabinet housing 2 until electrical engagement with electrical terminal assembly 21 occurs.

The vacuum-type contactor 7 is designed for starting and controlling three phase, 50-60 cycle alternating-current motors. The voltage may, for example, be 6,600 and the contactor-closed continuous rating in amperes 360.

FIG. 3 illustrates in side elevation the right-hand side 55 of the truck-mounted vacuum-type contactor assembly 7. As illustrated in FIG. 3, it will be observed that there is provided a direct-current operating magnet 57 having a direct-current magnet coil, or operating coil 59. Associated with the magnet structure 57 is a rotatable magnet armature 61 which makes abutting engagement when the operating magnet 57 is energized with the magnetic pole-face 63. The lower end 61a of the rotatable magnet armature 61 is affixed by a clamp casting 65 and a key 67 to the external end of an operating shaft 69, as shown. Also affixed to the operating shaft 69 is an electrical interlock pushrod 71 which operates an electrical interlock 73, the purpose for which will be more apparent hereinafter. In addition, FIG. 3 shows a protective resistor 74 which is inserted into the series magnet coil circuit 57 (FIG. 34) when the armature 61 has reached its fully-closed position against the pole face 63, as illustrated by the full lines in FIG. 3. Additionally, there is illustrated in FIG. 3 another interlock 77, the purpose for which will appear more fully hereinafter. Also FIG. 3 illustrates an isolating-switch mechanical interlock arm 78, which is operable by a downwardly-extending interlock rod (not shown) extending downwardly and operable by the isolating-switch assembly 3 (FIG. 11).

FIG. 3 shows that, generally, the truck-mounted contactor assembly 7 comprises two side metallic support plates 80 and 81 interconnected by a front U-shaped metallic support channel member 83, which is more clearly illustrated in FIG. 5 of the drawings. Also FIG. 3 shows the lower stab assembly 45 which interconnects the contactor assembly 7 with stationary load terminals 21 (FIG. 2) for operating an external piece of equipment, such as an electrical motor, for example.

FIG. 4 illustrates the other, or left-hand side 85 of the vacuum-type contactor assembly 7, which includes the other side metallic support plate 80, the two wheels 49 an interlock bar 87 associated with the levering-in mechanism, (not shown) which constitutes no part of the present invention. Also FIG. 4 illustrates the control transformer 33 which reduces the voltage from the

line terminals L1, L2 and L3 to a suitable lower voltage level for operating the magnet coil 59 of the operating-magnet structure 57. Additionally, FIG. 4 shows the interphase barriers 89-92 a flange support plate 95 for supporting the transformer 33 and also a fuse block 97 for the control circuitry 31.

FIG. 5 illustrates a view looking into the front of the truck-mounted vacuum-type circuit-interrupter assembly, or contactor assembly 7. It will be observed that the armature 61 of the operating magnet 57 is affixed to the external end of the operating shaft 69 and effects the rotatable operating motion thereof. The operating shaft 69 is, of course, journaled in suitable bearings 99, 101 provided on the inner sides 80a, 81a of the two metallic side support plates 80 and 81. FIG. 5 more clearly shows the fuse block 97, previously mentioned in connection with FIG. 4, and also the control transformer 33 for the control circuitry 31.

It is, of course, desirable to provide contact-closing spring pressure for each of the individual pole-units 39, 41 and 43 in the closed-circuit position of the contactor assembly 7, as illustrated in FIG. 6 of the drawings. Each pole-unit 39, 41 or 43 is provided with its own individual vacuum-interrupter unit 103 and a pivotally-mounted rotatable contact operating arm 105, which is pivoted upon a stationary pivot pin 107 extending between the two downwardly extending flange portions 108, 109 of a U-shaped lower interrupter support 110, the configuration of which is more readily apparent from a study of FIGS. 28-30 of the drawings.

The rotation of the rotatable contact arm 105 is effected by a laterally-extending cross-bar 112 which is moved in generally a vertical direction by two spaced crank-arms 114, 116 the latter being affixed to and rotatable with the operating shaft 69. FIG. 5, taken in conjunction with FIG. 6, more clearly shows the structure of the laterally extending cross-bar 112. As illustrated in FIG. 6, it will be observed that the cross-bar 112 is preferably of metal, and in this particular instance has a square cross-section, as shown, having end pivot-pins 118, the latter being apparent from a study of FIG. 5 of the drawings.

The cross-bar 112 is fixedly secured to an insulator support 120 individual to each of the three pole-units 39, 41, and 43 as more clearly illustrated in FIG. 5. The insulator support 120, in turn, supports an abutment member or in this particular instance a plate 122, for example, having a configuration more clearly apparent from a study of FIG. 10 of the drawings. FIG. 10 illustrates an exploded view of the contact-pressure spring assembly 124 and the relationship between the abutment member or plate 122 and a rotatable reverse-current loop-arm assembly 126, again the configuration of which is more clearly apparent from a study of FIG. 10 of the drawings.

As well known by those skilled in the art, it is desirable to supply contact spring pressure on the separable contacts in the closed-circuit position of the interrupter 103. This spring pressure, which is provided in the instant invention, is afforded by a compression spring 128 illustrated in FIGS. 6 and 10, and interposed between the abutment plate 122 and an upper movable spring seat 130, which straddles the two contact-actuating arms 105a, 105b, which collectively constitute the movable contact-actuating arm 105 of the interrupter assembly 7.

It will be observed, in connection with FIGS. 6, 7 and 9 of the drawings, that a contact drive pin 132 passes

through the two leg portions 105a, 105b of the movable contact-actuating arm 105 and, additionally, passes through a pair of apertures 134 provided in the rotatable reverse-current actuating arm 136. In other words, the same pivot pin 132 passes through the two leg portions 105a, 105b of the contact-actuating arm 105 and also through the leg portions 136a, 136b constituting the reverse-current arm-assembly 136, thereby enabling a force to be exerted at the pivot pin 132 in the contact-welded condition of the separable contacts 138, 139 under certain conditions, as more fully described hereinafter. In the welded contact position with the magnet deenergized, the fulcrum point is at 107 and the opening force is exerted at the pivot pin 132, as shown in FIG. 20.

With reference to FIGS. 7, 9 and 10 of the drawings, it will be observed that there is provided an overtravel adjusting nut 140, which is threaded upon the upper end 142a of a contact-pressure stud 142, the lower end of which is secured into the upper end of the insulator support 120. Thus, in the closed-circuit position of the vacuum-interrupter assembly 7, as illustrated in FIG. 7, the contact compression spring 128 is compressed, thereby applying contact-closing pressure between the separable contacts 138 and 139, the overtravel adjusting nut 140 accommodating the "wide" travel distance by continued closing travel of the contact-actuating arm 114. Thus, FIG. 7 illustrates the closed-circuit position of the interrupter device 7 with the operating magnet 57 energized and the compression spring 128 providing the desired contact pressure in the closed-circuit position of the device.

It will be obvious that during the opening operation, the operating shaft 69 will rotate in a counterclockwise direction, as viewed in FIG. 7, carrying downwardly with it the two operating arms 114 and 116 together with the cross-bar 112 and the three insulator supports 120. Also carried downwardly will be the abutment plates 122 and the contact pressure studs 142 until the overtravel adjusting nuts 140 engage the yoke portions 130 of the contact actuating arms 105, as illustrated in FIG. 9 of the drawings. Assuming that there does not exist a welded condition at the separable contacts 138, 139, the operating mechanism 144 will continue its counterclockwise opening movement carrying the separable contacts 138, 139 to their fully-open circuit position, as illustrated in FIG. 9 of the drawings.

The interrupter unit 103 may be of any suitable type manufactured commercially by a number of companies, and, in general, comprises an evacuated envelope 145 having end metallic plates 146, 147 hermetically sealed to the ends of the insulating envelope 145, such as a ceramic sleeve, for example. The vacuum "bottle" 103 is provided having supporting stud portions 149, say three in number, for example, extending upwardly and downwardly, as illustrated in FIGS. 7 and 9, and also having the movable contact stem 150 extending externally, as illustrated in FIGS. 7 and 9. In its manufactured component assembly form, it is, therefore, provided in a form enabling its ready mounting by the six mounting studs 149 and the movable contact 139 may be opened and closed by an actuating clamping portion 152 secured to the extending end 150a of the movable contact stem 150. The present equipment utilizes preferably, one of these manufactured "bottles" 103 for each pole-unit 39, 41, 43. As illustrated in FIG. 6, there is provided an upper interrupter support casting 154, cast, in this particular instance, of aluminum,

which has a horizontally-extending apertured support-flange portion 154a having mounting holes 154b therein to accommodate the three upwardly-extending mounting studs 149, the latter, as mentioned, constituting a part of the manufactured bottle 103.

Mounting nuts 156 threadedly secure the support-flange portion 154a of the casting 154 to the vacuum "bottle" 103 and maintain it fixedly in a proper position. The casting 154, in addition, has a pair of downwardly-slanting support arms 154c, which are interconnected by a second supporting flange portion, or yoke portion 154d, the latter being affixed to an upper insulator support 158 (FIG. 6) and to a metallic conductor support strap 160, the latter being securely mounted to an upper fuse-finger terminal assembly, generally designated by the reference numeral 162, and illustrated more clearly in FIG. 6 of the drawings. As illustrated in FIG. 11, the fuse-finger assembly 162 accommodates a power fuse 164 for each of the individual pole-units 39, 41, 43 of the equipment 7. A fuse-finger contact-pressure spring 166 is utilized, as illustrated in FIG. 6, supported between the pivotal fuse-finger portion 168 of the terminal assembly 162 and a spring seat 170 associated with a mounting bolt 172, the latter extending through a vertically disposed insul spacer block 174, the latter being secured by mounting bolts 172, 176 to a laterally-extending insulating support plate 178 of the frame 180. In addition, a metallic angle 181 is provided to rigidly interconnect the horizontally extending line-connection strap 160 with the horizontally extending conductor strap 182, FIG. 6 again showing this construction more clearly. A mounting bolt 184 extends vertically through the several component parts, as also shown in FIG. 6.

Fixedly secured to the upper extremity of a line-connection strap 160 is a terminal clamp 186 having a clamping portion 186a which encircles the upper extending end 188 of the stationary contact stem 189, as more clearly shown in FIG. 7. Due to the inherent flexibility provided by the line-connection strap 160 (FIG. 7), there is not exerted any stress nor torqueing action upon the stationary contact stem 188. However, with reference to FIG. 7, it will be observed that the bottle structure 103 itself is rigidly supported by the relatively massive and heavy upper interrupting casting support 154.

To counteract the inward closing force exerted because of the evacuated environment 190 within the evacuated enclosure 145, a kickout spring 192 is provided to compensate for the atmospheric pressure, the latter, of course, tending to force the separable contacts 138, 139 into the closed-circuit position, as illustrated in FIG. 7. The kickout spring 192 is interposed between a lower metallic washer 193 and the upper end of contact operator 152.

With reference to FIGS. 6, 7 and 9 of the drawings, it will be observed that there is provided at the lower end of the contactor-assembly 7 a reverse-current connector-assembly 126 comprising a generally loop-shaped flexible connector 195 having an upper terminal 196 fixedly secured by a connector bolt 197 to the lower end of the movable contact operator 152. The flexible connector 195 extends rightwardly, as viewed in FIG. 7, into a loop portion "L," and then extends toward the left, as viewed in FIG. 7, to be secured by a connector bolt 199 to the mid-portion 200 (FIG. 12) of a stationary U-shaped current-feeding member generally designated by the reference numeral 201 and having a con-

figuration more readily apparent from a study of FIGS. 12-14 of the drawings.

With reference to FIG. 16 of the drawings, it will be observed that placing the load-connection feed member 203 toward the front of the contactor assembly is commercially inappropriate. Also, as set forth in FIG. 17, providing the construction as set forth therein, with a relatively close spacing "S" between the stationary portion 205 of the reverse-current loop-connector 207 and the feed-strap member 208 provides an undesirable neutralization effect, as determined by the distance "S" in FIG. 17.

The more desirable form is as indicated in FIG. 18 of the drawings, where the current-feed structure 201 comprises a pair of stationary L-shaped leg members 210, 211 bolted, as at 212, to the side walls 214, 215 of the lower interrupter casting support 216, and having a bight portion at the front thereof, designated by the reference numeral 200. The bight portion 200 is electrically connected to the lower terminal 198 of the loop-shaped reverse-current loop assembly 126, as indicated more clearly in FIG. 9, which has the desirable advantage, as set forth in FIGS. 21 and 22 of the drawings, namely an augmentation of the upper movable flexible strap portion 221 by the magnetic field around the leg portions 210, 211 of the L-shaped reverse-current feed structure 126.

It will be observed that the reverse-current loop force "F" acts to break contact welds when the magnet structure 57 is de-energized, as is the condition set forth in full lines in FIG. 20 of the drawings. Under this particular state of affairs, the force "F" acting is such as to create a fulcrum point at the pivot point 107, thereby tending to create a counterclockwise rotative action upon the reverse-current arm 136, thereby bearing against the abutment plate 122, and assisting the accelerating springs 128 and the operating mechanism 144 in effecting a separation of the contacts 138, 139 within the vacuum-interrupter 103.

By avoiding the utilization of relatively-heavy springs, which in and of themselves would be capable of breaking welds, avoidance of a heavy operating magnet 57 is advantageously obtained. That is, if relatively heavy accelerating springs 128 are utilized, it would take a considerably stronger operating magnet 57 to effect their compression, and thereby bring about the closed-circuit condition of the contactor assemblage 7.

In the closed-circuit position of the interrupter, as shown in FIG. 18, with the operating magnet 57 energized, the fulcrum point is relocated so as to effect a desirable increase of pressure at the separable contacts 138, 139 during the attainment of heavy-fault current conditions. At this time the fulcrum point is at the left-hand tip of arm 136, with reference being had to FIG. 18 of the drawings. In other words, the fulcrum point is at the tips of 136b and the force is at pin 132, as shown in FIG. 18.

With reference to FIG. 11, the flow of electrical power through the starter 3 can be traced by referring to FIG. 11, where the starter 3 is shown in the energized position. The line stab assembly 19, mounted at the back of the cabinet 2 also serves as the starter line terminals L1, L2 and L3. The stabs themselves are engaged by the fuse jaws 223 of the isolation switch 3 which is mounted on rails at the top of the cabinet 2. The line ferrules 224 of the Type CLS power fuses 164, clip into the fuse jaws, and the load ferrules 226 fit into the fuse holders 162 which are part of the contactor

line terminals. Power flow through the contactor 7 is from the load ferrules 226 of the power fuses 164, through the interrupter contacts 138, 139 shunt 195 and then to the contactor load terminals 45. The contactor 7 is mounted on rails 53 in the lower part of the cabinet 2, immediately adjacent to the current transformers 27, which are bolted to a panel 9 in the side of the cabinet 2, with the load terminals 29 for the starter 1.

Spring-loaded contact jaws 228 (FIG. 6) mounted on the contactor load terminals 45 plug into a lower stab assembly 21, providing a convenient connection to the motor load terminals T1, T2 and T3.

Electrical protection is provided by the Type CLS power fuses 164 and by the overload relay 230. The CLS current limiting power fuses 164 have a special time/current characteristic for motor service, and this characteristic is coordinated with the characteristic of the overload relay 230. Currents greater than full load motor current, up through locked rotor current, will operate the overload relay 230 and trip the contactor 7 before the fuses 164 blow. This prevents unnecessary blowing of the fuses 164. Assuming the interrupting capacity of the contactor 7 is 50,000 KVA, the power fuses 164 must operate faster than the overload relay 230 when the KVA exceeds this value, in order to prevent damage to the contactor 7. In all faults above 50,000 KVA and within the rating of the equipment, the CLS fuses 164 will operate first.

The current transformers, overload relay heaters, and power fuses are coordinated with the motor characteristics, so that the starter 1 must be used with the motor for which it was designed. Motors with special characteristic or loads requiring special protection often require other or additional protective relays.

Vacuum contactors are relatively new on the market and have enjoyed only limited success due to several shortcomings.

In an effort to minimize the most serious of these shortcomings, the vacuum interrupter manufacturers have found it necessary to use contact materials which are susceptible to welding.

The welding problem, however, can be minimized by the use of contact and weld breaking forces approximately ten times those usually found in a conventional air break contactor of comparable rating.

Vacuum interrupters having the most desirable interrupting characteristics and longest contact life have been found to weld at currents considerably below their interrupting limit, so the interrupting rating of a contactor using these interrupters is limited by the ability of the actuating mechanism to overcome the welding problem rather than by the arc interrupting ability of the interrupter.

A three-pole contactor having a magnet and frame assembly proportioned to meet the design requirements of the requirements of the vacuum interrupter and still have a reasonable mechanical life would be much too large and costly to compete with existing air-break contactors which require only a fraction of the contact force. As a result of this "squeeze," presently available vacuum contactors are a design compromise which do not completely satisfy the requirements of the vacuum interrupter and as a result do not perform as well as existing air-break contactors.

The very high contact forces mentioned above are required only when it is necessary to obtain the maximum momentary rating of the vacuum interrupter

which is in the event of a power system fault. Since the contactor may seldom see this condition in actual service, a contactor designed to continuously provide these high forces would represent a rather inefficient use of space and material.

A reasonable-sized magnet coupled to the interrupter shaft through a toggle mechanism or other system of levers could be advised to develop high contact force, but the high mechanical advantage of this mechanism would act to reduce the contact operating speed far below the values recommended for the vacuum interrupter. The high mechanical advantage of this mechanism would, in addition, result in low contact overtravel which in turn would make frequent adjustment of contact overtravel necessary.

Reverse current loops similar to the one shown in FIG. 15 have been employed in the past to increase contact force under heavy fault conditions, but have the tendency to override the operating magnet. A reverse current loop 232 (FIG. 15) of this type, designed to supply the required contact forces of a three-pole vacuum contactor, would exert so much force that the reverse current loop 233 would hold the contacts and magnet closed even after the magnet is deenergized. A weak reverse current loop 233 of this type would not hold the contacts closed, but would act to reduce opening speed and weld-breaking forces, which is also undesirable.

In the disclosed vacuum contactor design 7 (FIG. 20), contact springs, operating magnet and contactor frame details are proportioned to provide contact forces sufficient to insure satisfactory performance under starting, running, and locked-rotor conditions for the maximum size motor with which the contactor 7 will be used.

These are the operating conditions the contactor 7 will see in everyday service, and the mechanical forces which the operating mechanism must be able to endure for a million or more operations.

Occasionally the contactor 7 may, however, be subjected to power-system fault conditions in which event the contactor 7 may be called on to interrupt or withstand peak currents 10 times or more the maximum peak currents encountered in everyday service under locked-rotor or motor-starting conditions.

In order to handle these higher currents, the vacuum interrupter 103 will require much higher contact and weld breaking forces than were necessary for handling the normal motor currents encountered in everyday service.

To obtain the higher mechanical forces only during an occasional system fault, without increasing the mechanical forces in effect in normal operation, a novel reverse current loop is provided as shown in FIG. 20.

This reverse-current loop 126 provides an increase in contact force and also weld-breaking force which is in proportion to the square of the current "I" flowing through the reverse current loop.

By properly proportioning the reverse-current loop 126, it is possible to provide a substantial increase in the contact and weld breaking forces under high-current conditions while only slightly increasing these forces under normal operating conditions.

The reverse-current loop 126 consists of upper and lower shunt legs 221, 222 plus parallel load connection bus bars 210, 211 as shown in FIGS. 12 and 20.

When current flows through the reverse current loop conductors 221, 222, the magnetic fields surrounding

these conductors 221, 222 react with each other to develop mechanical forces on the various conductors.

The lower horizontal leg 222 of the shunt and the parallel load connection bus bars 210, 211 are restrained by non-movable parts of the support structure 180, while the upper shunt leg 221 is free to move upward until it strikes the right-hand end of the reverse-current loop-arm 136.

When the contactor 7 is subjected to a power system fault, of high current magnitude, the reverse current loop 126 will apply a force upward on the right-hand end of the reverse-current loop-arm 136 which will in turn pry the interrupter contacts 138, 139 closed as shown in FIG. 17 assuming the contactor magnet 57 remains closed.

A second reaction of the reverse-current loop-arm 136 is to apply a downward force on the contact spring support plate 122 which will in turn increase the opening velocity of the magnet and cross-bar assembly 112 once the magnet 57 is de-energized.

When the magnet 57 is released, the moving assembly is accelerated by the combined forces of the contact springs 128 and reverse current loop 126 until there is no gap at the contact overtravel adjusting nut 25 as shown in FIG. 20.

At this point, the kinetic energy of the moving system imparts a hammer blow to the contact actuating arm 105 which acts to break any contact welds which might exist.

When the overtravel adjusting nut 140 makes contact with the upper contact spring seat 130, as shown in FIG. 20, the function of the reverse current loop 126 automatically takes a complete reversal to apply an additional contact opening force to the interrupter 7 rather than a contact closing, as it previously had done when the magnet 57 was closed.

Use of a flexible shunt 195 doubled back on itself in a conventional manner as shown in FIG. 16 brings the load connection 203 out the front of the contactor, 40 which is undesirable for use with plug-in devices.

Doubling the load connection back under the lower leg of the shunt 195 as shown in FIG. 17, acts to weaken the magnetic fields and mechanical forces of the reverse current loop 207 unless dimension "S" is 45 made relatively large.

The disclosed design employs a novel arrangement of the current-carrying parts 210, 211 of the reverse current loop 126 which makes it possible to bring the load connections 45 out at the rear of the contactor 7 and at the same time increase rather than decrease the force of the reverse current loop as shown in FIG. 22.

In this design the connection from the contactor load terminal 45 to the lower leg 222 of the shunt 195 is divided into two parallel legs 210, 211 which straddle and 55 are mounted at the same elevation as the upper leg 221 of the shunt.

The magnetic fields of the two parallel connections 210, 211 to the load terminal 45 combine with the magnetic fields surrounding the shunt 195, as shown in FIG. 60 22 to shape and to strengthen the resulting magnetic field of the reverse current loop 126 in such a manner that the net reverse-current loop force "F" is greater than for the conventional reverse-current loop shown in FIG. 16.

A kickout spring 192 is mounted directly on the contact shaft 150 of the interrupter 103 to take up the play between the contact actuating mechanism 144 and the interrupter contacts 138, 139. Without a kickout

spring 192 in this location, the contacts 138, 139 could touch momentarily under low contact force conditions while play is being taken up in the operating mechanism 144. Play between the contacts and operating mechanism 144 would aggravate the contact erosion and welding problems both on the opening and closing operations.

The kickout springs 192 also minimize armature bounce on opening and in addition are proportional to apply sufficient load on the magnet 57 at open gap position to prevent the magnet 57 from picking up unless its operating voltage is sufficient for the magnet 57 to seal-in from the contact-touch position.

Each pole 39, 41 and 43 of the contactor may be installed or removed from the contactor as an individual subassembly, so that it may be efficiently assembled or maintained at a work-bench rather than in the contactor 7.

The interrupter unit itself may also be installed or removed from the contactor as a smaller sub-assembly consisting of the interrupter 103, its support 154, moving contact actuating arm 105, and reverse current loop details 126 as shown in the exploded view of FIG. 10.

In order to obtain maximum mechanical life of the interrupter bellows 235 and also avoid friction between the interrupter contact shaft 150 and its bushing, it is important that the relationship between the contact drive pin 132 and the pivot pin 107 for the contact actuating arm 105 be accurately maintained.

To accomplish this, the interrupter 103 and the contact actuating arm 105 are both mounted on a single rigid mechanical detail 110 which can be accurately manufactured. This detail 110 is the lower interrupter mounting bracket shown in FIGS. 28-30.

In connection with the above alignment of parts, it is also desirable that the contacts 138, 139 touch when the contact drive pin 132 is on the same horizontal centerline 237 as the pivot pin 107 for the contact-actuating arm 105.

When the interrupter sub-assembly is being assembled, the kickout spring 192 is placed over the contact shaft 150 and then compressed by the contact operator 152 which in turn is held in place by the shoulder bolt 239. The shoulder bolt 239 is only tightened finger tight so as not to apply excessive torque to the interrupter shaft 150 and bellows 235.

The contact operator 152 and shoulder bolt 239 design is coordinated in a manner that the shoulder bolt 239 cannot clamp the contact operator 152 to the contact shaft 150, but instead permits the contact operator 152 to rotate freely on the contact shaft 150 without applying torque to the contact shaft 150 when the contact operator 152 is being lined up with the contact-actuating arm 105.

After the contact drive pin 132 is installed, the contact actuating arm 105 is depressed to take up the play between the contact drive pin 132 and contact shaft 150 following which the contact operator 152 is clamped to the contact shaft 150 by tightening the clamping bolt 241.

In normal service, the contact shaft 150 will be actuated through the clamped joint between it and the contact operator 152, but should this joint fail the contacts 138, 139 will then be closed by compression of the parts between the drive pin 132 and the end 150a of the contact shaft 150, and opened by the shoulder bolt 239.

One of the objects of the present invention is to prevent excessive torque from being applied to the shaft 150 of the interrupter 103 during maintenance and/or assembly since torque may destroy or shorten the mechanical life of the interrupter bellows 235.

The shoulder bolt 239 acts as an assembly fixture to compress the kickout spring 192 during assembly while still allowing the contact operator 152 to be rotated as required to install the contact drive pin 132. In operation the shoulder bolt 239 in addition acts as a safety device to insure opening of the contacts in the event the contact operator 152 is not securely clamped to the interrupter contact shaft 150.

The interrupter 103 is rigidly supported at its upper end, which contains the interrupter stationary contact 138 so as to avoid transmitting contact forces through the walls 145 of the interrupter 103. The moving contact end 150 of the interrupter 103 in addition is clamped to the stationary portion of the pole assembly to provide lateral stability. Clamping of the lower end of the interrupter sub-assembly "SB" is accomplished by means of an oversized open slot 243 which compensates for the manufacturing tolerances of the interrupter 103 and also simplifies installation and removal of the interrupter sub-assembly "SB."

Manufacturing tolerances on the interrupter length dimension "X" are rather large, so the vertical locations of the lower ends of the interrupter 103 may vary considerably from contactor 7 to contactor 7 and from pole to pole. Since the operating mechanism 144 for each pole is mounted on the moving contact end "E" of the individual interrupters 103, rather than on some fixed portion of the pole assembly, this is of little consequences.

In the event the interrupter length "X" is found to be other than its nominal value, the final lengths of the contact springs 128 will also vary from their nominal value resulting in either high or low contact forces.

The average contact force in the case of a multiple-pole contactor, as shown in the drawings, can, however, be corrected by adjusting the angular position of the magnet armature 61 on the operating shaft 69 so that the correct average contact spring length and force 128 is obtained when the magnet 57 is sealed-in.

Angular position adjustment of the magnet armature 61 is a standard feature of an existing air-break contactor magnet 57 applied to the disclosed vacuum contactor 7.

Variations in contact forces between poles existing after the magnet adjustment 61 has been made will fall within allowable limits if the contact springs 128 are designed to have a low spring rate.

NON-TORQUE ACTION EXERTED BY SHOULDER-BOLT 239

To avoid imposing torque action upon the movable contact stem 150 and thereby exerting corresponding torque action upon the bellows 235, the utilization of a novel shoulder-bolt 239 is provided. The construction of the shoulder-bolt is set forth in FIGS. 9 and 23 of the drawings. It will be observed that the bore 245 of the contact-shaft operator 152 has a relatively loose fit on the contact stem 150 as shown in FIG. 23, the shank 239a of the shoulder bolt 239 has a loose fit at "C" with the movable contact operator 152. The shoulder-bolt 239, for example, may have an Allen head with an enlarged portion 239a and a reduced portion 239b with a shoulder 247 therebetween, so that the shoulder-bolt,

when tightened, will force washers 249 (FIG. 10) against the lower extremity 150a of the moving-contact shaft 150 of the vacuum-type interrupter 103. This is shown in FIG. 23. The number of washers 249 is arranged to accommodate the tolerances provided between the different movable contact shafts 150 of the several pole-units 39, 41 and 43. Once the shoulder-bolt 239 is tightened, the contact-shaft operator 152 is moved manually upwardly, so that there is no clearance at the point "D" in FIG. 23. Then the clamping bolt 241 of FIG. 10 is tightened, so that the movable contact shaft 150 is operated by the contact-shaft operator 152, the latter having the apertures 250 provided therein to accommodate the center-line of the contact-drive pin 132. As a result, there is no torque action exerted either upon the movable contact shaft 150, or the bellows 235 located interiorly of the vacuum envelope 103. There may, of course, be relatively wide tolerances provided in the vacuum-bottle manufacture, and the foregoing arrangement permits a desirable accommodation of these tolerances.

VACUUM-BOTTLE TOLERANCES

Due to the wide latitude of the tolerances provided in the manufacture of the vacuum bottles 103, it is desired not to impose any stress upon the ceramic envelope 145, or to effect the breakage of any of the hermetic seals 251. To effect this end, an accurately machined lower-interrupter support-plate 110 having the pivot apertures 252 provided therein is supplied. These pivot apertures 252 may be accurately machined, and once the vacuum bottle 103 is fixedly secured by the upper interrupter casting 154, as a first operation, subsequently, as a separate operation, the U-shaped accurately-machined support plate 110 is secured into place by the lower three mounting bolts 149. The pivot-pin 132 may then be accurately located with respect to the lower interrupter support 110 because of the accurate machining of the pivot apertures 252 therein.

This will accurately locate the contact-actuating lever 105 and, additionally, accurately locate the contact-stem driving pin 132. As mentioned previously, the contact-shaft clamp bolt 241 is tightened as a final operation after previous assemblage of the contact-pivot pin 132 and tightening of the shoulder bolt 239.

WIRING CIRCUIT DIAGRAM FIG. 34

Included in the wiring circuit diagram of FIG. 34 is a power-operated main contactor 7 with separable power contacts 138, 139 to connect the three-phase load-lines T1, T2, T3 to the power-line conductors 254, 255 and 256, which are normally connected to the main supply lines L1, L2 and L3, through a disconnecting or isolating switch 3 including an arrangement of main power fuses 164 and sets of complementary disconnecting contacts 223 (FIG. 11).

Contactor 7 includes an electromagnetic operator 57 having a coil 59, which is energized by a rectifier 259 in response to the operation of a normally biased-open push-button "START" switch 261. Closure of the "START" switch 261 energizes a relay 263 whose normally-open contacts 265 and 267, respectively, connect the output of the rectifier 259 to the operator 59, and the input of the rectifier 259 to the secondary 269 of a stepdown transformer 44, whose primary 271 is connected across one phase of the main power-lines L1, L2 and L3. The input to the primary 271 includes fuses 273.

The entire control circuit may be energized from either the transformer 269 or a separate source 275, see FIG. 34. The low-voltage control circuit is normally energized from the transformer secondary 269, but may also be energized by a separate source of control power 275 for test purposes. Included in the output circuit of rectifier 259 are the normally-open contacts 265, male-female type plug disconnects 277, and resistor 74 shunted by a delayed-break auxiliary contact 281 mounted on the magnet assembly 57.

A hold or latch circuit 283 is shunted across the "START" button 261 and includes male-female plug-type disconnects 285 and normally-open contacts 287, which are operated to close the circuit 289 across the "START" button 261 when contactor 59 is operated, thereby holding relay 263 and consequently contactor 59 in the operated energized condition.

When contactor 7 closes, delayed-break auxiliary contact 281 opens to insert protective resistor 74 in series with the holding coil 59.

The thermostatic switch 230 is an overload switch and responds to the overload current conditions of the load lines T1, T2 and T3, as manifested in the heating of resistors (not shown) energized respectively from the current transformers 27.

From the foregoing description it will be apparent that there has been provided an improved operating mechanism for the separable contacts of a circuit-interrupter, particularly applicable to one of the vacuum-type. Although the instant invention has been described in connection with a vacuum-type circuit-interrupter 103, it will be obvious to those skilled in the art that certain principles, involved in the present disclosure, are pertinent to many other types of interrupter units, say those of the air-break type, such as illustrated in FIGS. 35-37. In these figures, gas-evolving materials are utilized instead of an evacuated environment. However, the desirable conditions for effecting the breaking of welds, or the addition of contact-pressure spring-force in the closed-circuit position of the interrupter, when the magnet is energized, is accomplished in a manner similar to that described heretofore.

With reference to FIGS. 35, 36 and 37 it will be observed that there is provided an air-break circuit-interrupter 300 having a hollow movable contact 301 pivotally connected, as at 132, to the movable contact-actuating arm 105 in a manner similar to that heretofore described in connection with FIGS. 6, 7 and 8 of the drawings. The movable contact 301 makes separable contacting engagement with a stationary contact member 303. The movable contact 301 moves downwardly during the opening operation through a generally tubularly-shaped member 305, composed of gas-evolving material, such as fiber, Delrin, Celcon, or like gas-evolving materials, as desired. In addition, a follower member 310, more clearly shown in FIG. 36, is secured by a metallic rod 312, as at the pivotal pin location 315.

During the opening operation, as in the manner heretofore described in connection with FIG. 7, the movable tubular contact 301 moves downwardly carrying with it the pivotally mounted follower member 310, the latter also being composed of gas-evolving material. An arc is established, and the arc is extinguished by the gas evolution resulting from the interaction between arc and the surrounding gas-evolving materials. An annular coil 320 may be electrically interposed between the relatively stationary annularly shaped contact 303 and a

lower-disposed arcing plate 325 to provide a radial magnetic field to bring about the rotation of the established arc, and consequently a more intimate engagement thereof with the surrounding gas-evolving material defining an annular arcing 330 chamber. As will be obvious from an inspection of FIG. 37, the annular arcing member is provided between the outer surface of the insulating follower member 310, composed of gas-evolving material, and the inner surface of the surrounding insulating cylindrical member 305 also composed of gas-evolving material, as mentioned.

The mechanism 144 may be of the same type as heretofore described in connection with the vacuum-interrupter 103. Also, in the closed-circuit position of the device, with the contacts 301 and 303 in a welded condition, again the augmentation of the reverse-current loop-arm assisting the operating mechanism 144 is desirable in breaking any welds established at the separable contacts 301 and 303.

Certain additional details regarding the interrupting structure only of FIGS. 35 and 37 are set forth in U.S. Pat. No. 2,294,801, issued Sept. 1, 1942 to Herbert L. Rawlins, and assigned to the assignee of the instant application.

Also, it will be observed that with the improved operation mechanism, and the reverse-current loop system, the function of the reverse-current loop-system changes in dependence upon whether or not the operating magnet 57 is energized, or is not energized. In the energized state of the operating magnet 57, an additional force is provided to maintain the contacts 138, 139 closed during the existence of heavy-fault-current conditions. When the magnet 57 is not energized, the fulcrum point changes, or is relocated to thereby provide, instead of a closing force, in this instance an opening force, which assist and augments the accelerating opening springs.

Although there has been illustrated and described specific embodiments of the invention, it is to be clearly understood that the same were merely for the purpose of illustration, and that changes and modifications may readily be made therein, by those skilled in the art, without departing from the spirit and scope of the invention.

I claim:

1. A circuit-interrupter including separable contacts at least one of which is movable, a movable operating stem supporting and operating said movable contact, a movable contact-operating arm having a pivotal operating connection with said movable operating stem, means pivotally mounting said movable contact-operating arm at a second stationary pivot-point, means defining a reverse-current movable arm also pivotally mounted on said first pivotal connection, flexible conducting strap-means having one end movable and electrically connected to said movable operating stem, said flexible conducting strap-means additionally having an actuating portion affixed to and movable with one end of the reverse-current movable arm, the other end of said flexible conducting strap means being maintained in a relatively fixed position to thereby provide a repulsion magnetic force between the legs of the reverse current-loop during heavy-fault-current conditions, operating means capable of being energized and de-energized including a contact-compression spring and an abutment member for effecting the rotation of said pivotally mounted movable contact-operating arm adjacent its free end about the second stationary pivot

point, and said reverse-current movable arm bearing upon said abutment member during non-energized conditions of said operating means, whereby weld-breaking forces are magnetically generated about a fulcrum point at said first pivotal connection, and whereby in the energized condition of the operating means there is no contact between the abutment member and the reverse-current movable arm and additional contact-closing forces are generated at the reverse-current flexible conducting strap-means.

5 2. The combination according to claim 1, wherein the operating means includes a support insulator having a threaded stud secured thereto passing through said abutment member, and a contact overtravel adjusting nut is threadedly secured to the end of said stud.

15 3. The combination according to claim 1, wherein the reverse-current supply circuit includes a generally U-shaped stationary circuit having stationary legs extending on the same general level as the flexible and movable portion of the flexible conducting looped-shape strap means.

20 4. The combination according to claim 1, wherein the reverse-current movable arm has a flexible strap retainer at its other end from the location of the bearing portion and maintains a fixed connection with said flexible conducting strap-means.

25 5. The combination according to claim 2, wherein the pivotally-mounted movable contact operating arm comprises two leg portions having a bight portion through which said stud passes, and which bight portion serves as one end of the contact-compression spring means.

30 6. The combination according to claim 1, wherein the circuit-interrupter is a vacuum-type circuit-interrupting unit.

35 7. The combination according to claim 6, wherein a kickoff spring encircles the movable contact operating stem and compensates for the surrounding atmospheric pressure tending to force the separable contacts closed within the vacuum interrupter unit.

8. The combination according to claim 4, wherein the reverse-current movable arm comprises a pair of leg portions which are secured together by said flexible strap retainer means.

40 9. The combination according to claim 1, wherein the second pivotal support is provided by a generally U-shaped stationary support plate member affixed to one end of the circuit-interrupter unit.

50 10. The combination according to claim 9, wherein the circuit-interrupter unit is a vacuum-interrupter unit, and the U-shaped support plate member has an aperture therethrough to accommodate the reciprocal opening and closing movements of the movable contact operating stem.

55 11. The combination according to claim 1, wherein the operating means includes a laterally-extending cross-bar having two end operating arm-portions which are actuated by an operating magnet.

60 12. The combination according to claim 11, wherein an operating shaft extends through a side support plate of the circuit interrupter and is actuated externally of the side support plate by the operating magnet.

65 13. The combination according to claim 3, wherein the reverse-current feed-circuit comprises two substantially L-shaped leg portions dividing the current in parallel and being disposed on the same general level as the flexible movable portion of the loop-shaped flexible conducting strap-means.

14. The combination in high-voltage motor-starter equipment of a truck-mounted assembly having a vacuum-type circuit-interrupting unit carried therewith, upper line-terminal means connected to one end of said vacuum-type interrupter unit, said one end of the vacuum interrupter unit accommodating the stationary contact thereof, load terminal means disposed at the lower end of said motor-starter equipment including a flexible loop-shaped strap-means connected to the lower-disposed movable contact stem of said vacuum-type interrupter unit, a U-shaped pivot support means secured to the lower end of said vacuum-type interrupter unit, a rotatable movable contact actuating arm having a first pivotal connection to one end of the movable contact stem, said contact arm being stationarily pivotally mounted upon a second pivot point provided by said U-shaped pivot support means, operating means capable of being energized or being non-energized for effecting the rotation of said contact-operating arm including contact-compression springs, a relatively rigid reverse-current weld-breaking arm pivotally mounted at said first pivot point to said movable contact operating stem and having a flexible loop-shaped portion for carrying the series electrical current through said vacuum-interrupter unit, said operating means including a bearing member making at times in the non-energized state of the operating means abutment with said rigid weld-breaking reverse-current arm, said loop having a relatively stationary portion so that the magnetic repulsion forces existing between the two sides of the loop will effect additional contact-closing forces in energized condition of the operating means and an opposite opening effect during the non-energized condition of said operating means to effect weld-breaking action and a consequent opening operation of the motor-starter equipment.

15. The combination according to claim 14, wherein the operating means includes an insulator support having an adjustable stud affixed thereto to accommodate

the contact-compression spring and also a contact-overtravel adjusting nut.

16. A circuit interrupter including separable contact means comprising at least one movable contact, a movable contact stem supporting and actuating said movable contact, a rotatable contact-actuating arm pivotally connected at a first movable pivot point to said movable contact stem and pivotally supported at a second stationary pivot point, means for effecting opening and closing motions of said contact-actuating arm (105) including an abutment portion (122), double-acting reverse-current loop-means comprising a pivotally-mounted actuating arm (136) pivotally connected to said contact stem (150) and having one end bearing on said abutment portion (122), said loop means carrying the series electrical current through said separable contact means and operable to effect a leverage action about said first pivot point during the closed-circuit position of the interrupter during the existence of heavy fault-current conditions to maintain the separable contacts closed under greater contact pressure, said double-acting reverse-current loop-means being operable at other times for a rotative leverage action about said abutment portion (122) for weld-breaking action exerted upon the separable contacts and consequent opening of the separable contact means.

17. The combination according to claim 16, wherein the double-acting reverse-current loop means includes a rotatable prying arm pivotally mounted about said first pivot point and having attached thereto a reverse-current loop having at least one flexible movable portion.

18. The combination according to claim 17, wherein a second portion of said reverse-current loop is stationarily mounted.

19. The combination according to claim 18, wherein the reverse-current feeding circuit comprises a pair of stationary parallel-arranged arms in the general plane of the movable portion of the reverse-current loop-assembly.
